SUB-CALIBER ASSEMBLY FOR FIREARMS

Victor Henri Wallenberg, Stockholm, Sweden

Application May 4, 1945, Serial No. 591,948
In Sweden April 28, 1944

31 Claims. (Cl. 42—19)

1

The present invention relates to fire-arms, and particularly to military rifles for shooting with miniature ammunition by means of an insertion barrel adapted to be inserted from the rear into the barrel of the rifle. The primary object of the invention is to provide means which render possible firing of several rounds without recharging by means of miniature ammunition, in a manner such that the hand motions required for the recharge movements of military rifles will be maintained as much as possible. In order to shoot with miniature ammunition, certain parts of a normal military rifle, that is the bolt, the floor-plate of the magazine and the appertaining magazine spring and follower, are exchanged for certain appropriate members. These members can be inserted and removed by simple hand movements.

The difficulties in firing several rounds without recharging with miniature ammunition in a usual military rifle or similar fire-arm are mainly due to the unflanged and inconveniently shaped miniature ammunition the shape of which is a result of the requirements for the cheap method of manufacture. Due to the shape and the small size of the miniature ammunition, extraction and ejection become difficult problems. Also the feeding of the cartridges from a strip or clip to the cartridge chamber is connected with difficulties if the cartridges are not positively guided during their entire feeding movements. Such guiding means are, however, difficult to realize.

It is a further object of the invention to provide a mechanism for the purpose indicated, in which neither extractors nor ejectors are needed and in which the cartridges may in advance be inserted into cartridge chambers which are successively brought into firing position.

These and further objects I attain by mechanism illustrated in the accompanying drawings in which:

Fig. 1 is a vertical section through the breech mechanism with appertaining parts of a military rifle of the Mauser type; Fig. 1a is a vertical section through the breech mechanism according to an embodiment of the invention with the various parts in the positions immediately after firing; Fig. 2 is a similar section with the parts in a position during the last part of the back movement of the bolt; Fig. 3 illustrates part of the novel device as viewed from below in the position according to Fig. 1a; Fig. 4 is a section on an enlarged scale of the bolt along the line IV, Fig. 1a; Fig. 5 is a section through the bolt along the line V in Fig. 1a; Fig. 6 illustrates the

2

bolt as viewed from above in Fig. 1a; Fig. 7 is a somewhat modified embodiment of the bolt; Fig. 8 is a vertical section of a slightly modified embodiment of the invention; Fig. 9 is a section taken substantially on the line IX—IX, Fig. 8; Fig. 10 is an enlarged section through part of the breech mechanism along the line X—X, Fig. 2; and Fig. 11 shows a modification of some parts shown in Fig. 1a.

Referring to Fig. 1, numeral 1 denotes the rear portion of the rifle barrel which is threaded into the bolt case 2. The bolt *a* is in usual manner connected with the bolt handle *b* and is combined with the guide sleeve *c* and provided with the striker *d*, striker nut *e*, cocking piece *f* and striker spring *g*. The normal magazine case *m* is closed at the bottom by the floor-plate *h*, and contains magazine spring *i* and follower *k*. It is deemed unnecessary to describe further details of the rifle, as such details are well known in the art and are not affected by the exchange required for shooting with miniature ammunition.

For shooting with miniature ammunition, the parts denoted by letters *a* to *k*, that is, the bolt and magazine spring with appertaining parts, are to be exchanged for devices to be described with reference to Fig. 1a.

Referring to Fig. 1a, numeral 1 again denotes the rear portion of the rifle barrel which is threaded into the bolt case 2. Into the bolt case, there is inserted a tube 3 in which the substitute bolt 4 is movable. The insertion barrel 5 for shooting with miniature ammunition is at its rear end located within the bolt cover, said rear end being surrounded by the tube 3. The inserted barrel 5 may be detachably connected with the tube 3, such as by means of a bayonet-clutch joint, shown in Fig. 11, in order to facilitate withdrawal of the insertion barrel from the rifle barrel. To this end, the tube 3 has a radial internal projection 52 adapted to engage a groove in the insertion barrel 5, said groove having an axial portion 53 and an adjoining portion 54 extending obliquely rearwardly. The tube 3 which at its lower portion is provided with an axial opening 6 is externally connected with a guide bar 7 (Figs. 3—5 and 10) which engages the normal axial guide groove 51 (Figs. 9 and 10) in the bolt case so as to prevent turning movement of the tube. The tube 3 is prevented from moving rearwardly due to the fact that the rear end 55 of the guide bar 7 abuts against a bolt stop 56 (Fig. 10) normally located on the left hand side of the rifle, which bolt stop is mounted on a pin 58 and adapted to be swung out against the action of a spring 57. When the

tube 3 is inserted into the bolt case, there will be a clearance of about $\frac{1}{2}$ of an inch as a result of the construction of the bolt stop. This clearance can be eliminated by making the groove of the above named bayonet-clutch oblique with respect to the axis of the insertion barrel as shown in Fig. 11, such that the tube can be forced back against the bolt stop by turning the insertion barrel.

The bolt 4 is in a manner known combined with a guide sleeve 8 and provided with a striker 9, striker nut 10, cocking piece 11 and striker spring 12. The bolt is intended to be operated by means of the bolt handle 13 in the manner usual in rifles of the type referred to. The bolt is to be locked in its forward end position by turning the bolt handle 13 through an angle of 90°. To this end, the bolt has an axial groove 14 and an adjoining peripheral groove 15 cooperating with a locking member 16 which is connected with the guide bar 7 secured to the tube 3 and which extends radially inwardly through an opening in the tube. The reactive pressure at firing will consequently not act upon the tube 3, but will be transmitted from the bolt at the forward wall 15a of peripheral groove 15 to the locking member 16 which abuts thereagainst and thence through the latter and guide bar 7 to the bolt stop without passing through the tube 3. The peripheral groove 15 extends through more than half the periphery and also serves as a recess cooperating with a lever 17 the upper end of which is extending through the opening 6.

For shooting with miniature ammunition, the floor-plate of the magazine case *m* and the magazine spring and follower are exchanged for a repeater device mounted on a magazine frame 18 which is open at the top and bottom. The frame 18 can be detachably fastened to the lower fitting 19 of the rifle in a similar manner as the normal floor-plate of the magazine case *m*. A lever or magazine carrier 20 is pivoted at 21 in the forward portion of the frame 18. Around the pivot 21, there is wound a spring wire one end 22 of which is connected with the magazine carrier 20 and tends to move the same towards the insertion barrel 5, whereas the other end 23 extends into an opening 24 in the frame in a manner such that it can be withdrawn from said opening and used as a handle for swinging the magazine carrier 20 out of the magazine space 25, as indicated at 23' in Fig. 2. The magazine carrier has mounted thereon an axle 26 located parallel to the pivot 21 and at right angles to the symmetrical plane through the axis of the barrel 1 of the rifle. On the axle 26, there is rotatably mounted a cartridge magazine 27 which, according to the embodiment illustrated, consists of a disc, drum or similar member which on its periphery is provided with a number of cartridge chambers 28, 29, 30, 31 and 32 for miniature ammunition. The said cartridge chambers are constituted by sleeves which are adapted partly to enter the rear mouth of the insertion barrel so as to constitute sealing members for the gas pressure. The sleeves preferably have such lengths that the forward edges of the cases of the projectiles discharged are located behind the forward edges of the sleeves, see Fig. 8, in order that the expansion of the cartridge cases due to the gas pressure and an extrusion of the material of the cases through a clearance, if any, between the cartridge chamber and the insertion barrel shall not obstruct removal of the cartridge cases from the cartridge

chambers. The axes of the cartridge chambers are located tangentially in the plane of rotation of the magazine. In the firing position, the respective cartridge chamber abuts against, and is guided by, the rear end of the insertion barrel, in which position the axes of the barrel and cartridge chamber are coinciding with each other.

The rotatable magazine is provided with pins 33 the number of which corresponds to the number of the cartridge chambers. These pins are adapted to render possible a limited rotational movement of the magazine 27. To this end, the pins are cooperating with a catch 34, which is pivoted, as at 35, on the lever 17 which engages the groove 15. The lever 17 is in turn pivotally mounted, as at 36, on the rear portion of the frame 18. The catch 34 has two fingers 37 and 38 adapted successively to engage the pins 33. The forward finger 38 is at its front end provided with an abutment 39. A similar abutment 40 is formed at the front end of the rear finger 37. A spring 41 wound around the pivot 36 tends, on the one hand, to turn the lever 17 towards the rear end position thereof, and, on the other hand, to turn the catch into engagement with the pins 33 of the magazine by means of an abutment 42 secured to the catch. The turning movement of the lever 17 in the direction away from the rotatable magazine is limited by the rear wall 43 of the magazine space 25.

The bolt 4 which is introduced into the rifle after the frame 18 together with the repeater device has been inserted into the magazine space 25, will during its forward movement turn the lever 17 in a clockwise direction until said lever, due to the action of the spring 41, will enter the groove 15. Thereupon, the bolt can not be withdrawn from the rifle, unless the frame and the repeater device are removed from the magazine space.

The mode of operation of the device described is as follows.

In Fig. 1a, the various parts are shown in their positions immediately after discharge of the projectile of the cartridge chamber 28, the bolt 4 being still in locked position with the handle 13 swung downward. The bolt is locked by means of the locking member 16 which engages the peripheral groove 15, see Fig. 4. The cartridge chamber 28 is by means of the bolt 4 pressed against the mouth of the insertion barrel 5. All of the cartridge chambers are filled either with cartridges or with cartridge cases. The cartridges or cartridge cases are consequently retained in their chambers in the magazine 27 during the repeating movements and firing as well as during the insertion or removal of the magazine into or from the magazine space.

When the bolt 4 in known manner is swung in an anti-clockwise direction, as viewed in Fig. 4, through an angle of 90° by means of the handle 13, the axial groove 14 will register with the locking member 16. Consequently, the bolt can now be moved back. At the same time, the lever 17 engaging the groove 15 will be swung back. The backward movement will come to an end when the lever 17 comes into contact with the rear wall 43 of the magazine space. During the backward movement of the bolt and the lever 17, the pin 33 located between the fingers of the catch 34 will be seized by the fingers 37 and 38. As a result thereof, the magazine will be rotated about the axle 26 in a counter-clockwise direction, as viewed in Fig. 1a. After a short rotational movement of the magazine, the next cartridge chamber 29

comes into contact with the lower face of the insertion barrel 5. Upon continued rotation of the magazine 27 by means of the catch, the cartridge chamber 29 will trail along the insertion barrel, and, at the same time, the magazine together with the axle 26 and the magazine carrier 28 will be swung downwardly and backwardly about the pivot 21, and the spring 22 will be compressed. Fig. 2 illustrates a position in which the cartridge chamber 29 is ready to get out of contact with the insertion barrel. During the last portion of the backward movement of the bolt from the position shown in Fig. 2 to the position in which the lever 17 abuts against the wall 43, the spring 22 forces the magazine carrier 28 and thus also the magazine in an upward and forward direction about the pivot 21. Consequently, the cartridge chamber 29 will enter the space between the bolt and the insertion barrel. Excessive rotational movement of the magazine due to its inertia is prevented, on the one hand, due to the fact that the next cartridge chamber 39 will trail along the insertion barrel so as to brake the rotational movement of the magazine, and, on the other hand, due to the fact that the next pin 33 will come into contact with the abutment 39 on the forward finger 38 of the catch. To the same end, the catch 34 may be arranged in a manner such that it resiliently abuts against the rotatable magazine so as to brake the rotational movement thereof. After the movements described, the magazine 27 has been rotated in an anti-clockwise direction through an angle which is somewhat greater than the angular distance between two consecutive cartridge chambers.

If, thereupon, the bolt 4 is again moved forth into its locking position, the pin 33 located between the fingers 37 and 38 will come into contact with the abutment 49 of the catch which will be moved in a forward direction by means of the bolt-actuated lever 17. Consequently, the magazine will be rotated through a small angle. As a result of this rotation, the cartridge chamber 29 will be moved towards the rear end of the insertion barrel, whereupon it will be forced against the mouth of the barrel by means of the bolt. When the bolt has been moved into its locked position, the striker spring 12 has been compressed in the usual manner, and the cartridge housed in the cartridge chamber 29 can be fired off. The recharging movement described is then repeated, until all of the cartridges have been fired off.

In order to insert new cartridges, the spring 23 is withdrawn from the opening 24, whereupon the magazine carrier 28 can be swung out from the magazine space together with the rotatable magazine 27. Thereupon, the cartridge cases still contained in the cartridge chambers can be removed therefrom and exchanged for new cartridges, or the rotatable magazine can be removed together with the cartridge cases and substituted by a new magazine already charged with cartridges. The magazine carrier 28 is then again swung into the magazine space, and the spring 23 is introduced into the opening 24. During the recharging operation, the catch 34 is, by means of the spring 41, maintained in a position suitable to the insertion of the rotatable magazine.

According to the modified embodiment of the bolt shown in Fig. 7, the axial groove 14a is entirely separated from the groove 15 and merges in a peripheral groove 14b. In this instance, the groove 15 is only intended for cooperation with the lever 17, whereas the grooves 14a and 14b co-

operate with the locking member 16 which, in this case, is assumed to be disposed towards the left into a position registering with the groove 14b. Due to this arrangement, the bolt is reliably guided even in its rearward end position in which the handle 13 is in an upright position.

The cartridge chambers may be slightly oval or conical or they may be provided with projections, in order that the cartridges during the recharging movements shall be safely retained in their respective cartridge chambers due to slight deformations.

In Figs. 8 and 9, there is shown a slightly modified construction of the insertion barrel 5. In this instance, the tube 3 is secured in proper position by means of a helical spring 45 inserted between the forward end of the tube 3 and a shoulder 46 on the insertion barrel, by means of which said barrel abuts against the rear end of the rifle barrel 1. The spring 45 forces the guide bar of the tube 3 against the bolt stop 56 of the rifle and thus prevents lost motion of the tube and insertion barrel. The insertion barrel has a number of radial grooves 47 spaced peripherally from each other. A pin 48 having a head 49 is adapted to engage either of the grooves 47. The head 49 is axially slidably in the guide groove 51 of the bolt case. The tube and bolt can be inserted and withdrawn together with the insertion barrel, since the tube and barrel are interconnected by means of the pin 48 and since the spring 45 axially acts upon the head 49 and thus maintains the pin 48 in engagement with one of the grooves 47.

Due to small, practically unavoidable inaccuracies in the manufacture of the insertion barrel, it will in most cases be found that the axis of the insertion barrel coincides with the axis of the rifle barrel in a certain angular position of the insertion barrel, while said axes are slightly deviating from each other in other angular positions of the insertion barrel. The proper angular position can be easily found by inspecting the hits on the target. If the grooves 47 are marked by numerals or letters, it can thus be ascertained which of the numerals or letters corresponds to the proper angular position, and the barrel can always be inserted in that position.

From Fig. 8, it will further be seen that the catch 34 has a downwardly extending portion 50 near its pivot 35. Said portion 50 constitutes a certain mass or weight which counteracts any tendency of the catch to be entirely swung out of engagement with the pins 33 as a result of very rapid repeating movements.

What I claim is:

1. A sub-caliber assembly for use in a bolt-action rifle of the type including a bolt, a bolt case, a fixed barrel secured to the bolt case, and a magazine case, said assembly comprising; an insertion barrel constructed and arranged to be at least partly inserted into the bore of said fixed barrel and having a smaller caliber than said fixed barrel, a substitute bolt, a cartridge magazine, means constructed and arranged to support said magazine in said magazine case, said magazine having a plurality of cartridge chambers for cartridges, and means responsive to the movement of said substitute bolt for bringing said cartridge chambers successively into firing position relative to said insertion barrel.

2. A sub-caliber assembly for use in a bolt-action rifle of the type including a bolt, a bolt case, a fixed barrel secured to the bolt case, and a magazine case, said assembly comprising; an insertion barrel constructed and arranged to be at least

partly inserted into the bore of said fixed barrel and having a smaller caliber than said fixed barrel, a substitute bolt, a cartridge magazine, means constructed and arranged to support said magazine in said magazine case, said magazine having a plurality of cartridge chambers for cartridges, and means responsive to the movement of said substitute bolt for bringing said cartridge chambers successively into firing position relative to said insertion barrel, said cartridge magazine being rotatable about an axis located at right angles to the symmetrical plane through the axis of said fixed barrel.

3. A sub-caliber assembly for use in a bolt-action rifle of the type including a bolt, a bolt case, a fixed barrel secured to the bolt case, and a magazine case, said assembly comprising; an insertion barrel constructed and arranged to be at least partly inserted into the bore of said fixed barrel and having a smaller caliber than said fixed barrel, a substitute bolt, a cartridge magazine, means constructed and arranged to support said magazine in said magazine case, said magazine having a plurality of cartridge chambers for cartridges, and means responsive to the movement of said substitute bolt for bringing said cartridge chambers successively into firing position relative to said insertion barrel, said cartridge magazine being rotatable about an axis located at right angles to the symmetrical plane through the axis of said fixed barrel, and the axes of said cartridge chambers being located tangentially in the plane of rotation of said cartridge magazine.

4. A sub-caliber assembly for use in a bolt-action rifle of the type including a bolt, a bolt case, a fixed barrel secured to the bolt case, and a magazine case, said assembly comprising; an insertion barrel constructed and arranged to be at least partly inserted into the bore of said fixed barrel and having a smaller caliber than said fixed barrel, a substitute bolt, a cartridge magazine, means constructed and arranged to support said magazine in said magazine case, said magazine having a plurality of cartridge chambers for cartridges, and means responsive to the movement of said substitute bolt for bringing said cartridge chambers successively into firing position relative to said insertion barrel, said cartridge magazine consisting of at least one disc rotatable about an axis located at right angles to the symmetrical plane through the axis of said fixed barrel, said cartridge chambers being located at the periphery of said disc.

5. A sub-caliber assembly for use in a bolt-action rifle of the type including a bolt, a bolt case, a fixed barrel secured to the bolt case, and a magazine case, said assembly comprising; an insertion barrel constructed and arranged to be at least partly inserted into the bore of said fixed barrel and having a smaller caliber than said fixed barrel, a substitute bolt, a cartridge magazine, means constructed and arranged to support said magazine in said magazine case, said magazine having a plurality of cartridge chambers for cartridges, and means responsive to the movement of said substitute bolt for bringing said cartridge chambers successively into firing position relative to said insertion barrel, in which position said cartridge chambers are abutting against and guided by the rear end of said insertion barrel, and in which position the axis of said insertion barrel is coinciding with the axis of the respective cartridge chamber.

6. A sub-caliber assembly for use in a bolt-action rifle of the type including a bolt, a bolt

case, a fixed barrel secured to the bolt case, and a magazine case, said assembly comprising; an insertion barrel constructed and arranged to be at least partly inserted into the bore of said fixed barrel and having a smaller caliber than said fixed barrel, a substitute bolt, a cartridge magazine, means constructed and arranged to support said magazine in said magazine case, said magazine having a plurality of cartridge chambers for cartridges, and means responsive to the movement of said substitute bolt for bringing said cartridge chambers successively into firing position relative to said insertion barrel, said cartridge chambers consisting of sleeves adapted partly to enter the rear mouth of said insertion barrel, whereby to constitute sealing members between said substitute bolt and said insertion barrel.

7. A sub-caliber assembly for use in a bolt-action rifle of the type including a bolt, a bolt case, a fixed barrel secured to the bolt case, and a magazine case, said assembly comprising; an insertion barrel constructed and arranged to be at least partly inserted into the bore of said fixed barrel and having a smaller caliber than said fixed barrel, a substitute bolt, a cartridge magazine, means constructed and arranged to support said magazine in said magazine case, said magazine having a plurality of cartridge chambers for cartridges, and means responsive to the movement of said substitute bolt for bringing said cartridge chambers successively into firing position relative to said insertion barrel, said cartridge chambers consisting of sleeves adapted partly to enter the rear mouth of said insertion barrel, whereby to constitute sealing members between said substitute bolt and said insertion barrel.

8. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and having a plurality of cartridge chambers for cartridges, and means responsive to the movement of said substitute bolt for rotating said cartridge magazine, whereby to bring said cartridge chambers successively into firing position relative to said insertion barrel.

9. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and

having a plurality of cartridge chambers for cartridges, and means responsive to the movement of said substitute bolt for rotating said cartridge magazine, whereby to bring said cartridge chambers successively into firing position relative to said insertion barrel, said pivot being located downwardly and forwardly of said axle.

10. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and having a plurality of cartridge chambers for cartridges, and means responsive to the movement of said substitute bolt for rotating said cartridge magazine, whereby to bring said cartridge chambers successively into firing position relative to said insertion barrel, said magazine carrier being adapted to be swung out of, and into, said magazine case through said frame.

11. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and having a plurality of cartridge chambers for cartridges, resilient means adapted to swing said magazine carrier towards said insertion barrel, and means responsive to the movement of said substitute bolt for rotating said cartridge magazine, whereby to bring said cartridge chambers successively into firing position relative to said insertion barrel.

12. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and having a plurality of cartridge chambers for cartridges, resilient means adapted to swing said magazine carrier toward said insertion barrel, and means responsive to the movement of said substitute bolt for rotating said cartridge magazine, whereby to bring said cartridge chambers successively into firing position relative to said insertion barrel, each of said cartridge chambers

being adapted during its movement into firing position to trail along the lower face of said insertion barrel, whereby to swing said magazine and magazine carrier against the action of said resilient means.

13. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and having a plurality of cartridge chambers for cartridges, resilient means adapted to swing said magazine carrier towards said insertion barrel, and means responsive to the movement of said substitute bolt for rotating said cartridge magazine, whereby to bring said cartridge chambers successively into firing position relative to said insertion barrel, said resilient means consisting of a spring wire wound around said pivot and having one of its ends secured to said magazine carrier, the other end of said spring wire being adapted to be detachably fixed to said frame and to be used as a handle for swinging said magazine carrier out of said magazine case.

14. A sub-caliber assembly for use in a bolt-action rifle of the type including a bolt, a bolt case, a fixed barrel secured to the bolt case, and a magazine case open at the bottom, said assembly comprising; an insertion barrel constructed and

arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and having a plurality of cartridge chambers for cartridges,

45 a first spring adapted to swing said magazine carrier towards said insertion barrel, a plurality of projecting pins on said magazine, the number of said projecting pins being equal to the number of said cartridge chambers, a catch member, a second spring adapted to bring said catch member into engagement with said projecting pins, and means responsive to the movement of said substitute bolt for actuating said catch member,

55 50 whereby to impart rotational movement to said magazine and to bring said cartridge chambers successively into firing position relative to said insertion barrel.

15. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame,

70 a magazine carrier normally placed in said maga-

zine case and mounted on said pivot, an axle secured to said magazine carrier, a cartridge magazine rotatably mounted on said axle and having a plurality of cartridge chambers for cartridges, a first spring adapted to swing said magazine carrier towards said insertion barrel, a plurality of projecting pins on said magazine, the number of said projecting pins being equal to the number of said cartridge chambers, an arm pivotally mounted on said frame, a catch member, a second spring adapted to bring said catch member into engagement with said projecting pins, said catch member being pivotally mounted on said arm, and said arm being connected with said substitute bolt and operable upon movement thereof, whereby to impart rotational movement to said magazine and to bring said cartridge chambers successively into firing position relative to said insertion barrel.

16. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and having a plurality of cartridge chambers for cartridges, a first spring adapted to swing said magazine carrier towards said insertion barrel, a plurality of projecting pins on said magazine, the number of said projecting pins being equal to the number of said cartridge chambers, a catch member, a second spring adapted to bring said catch member into engagement with said projecting pins, said substitute bolt having a recessed portion, and an arm pivotally mounted in said frame and engaging said recessed portion, said catch member being pivotally mounted on said arm and adapted to impart a limited rotational movement to said magazine.

17. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of said fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and having a plurality of cartridge chambers for cartridges, a first spring adapted to swing said magazine carrier towards said insertion barrel, a plurality of projecting pins on said magazine, the number of said projecting pins being equal to the number of said cartridge chambers, a catch member, a second spring adapted to bring said catch member into engagement with said projecting pins, said substitute bolt having a recessed portion, and an arm pivotally mounted on said frame and adapted to engage said recessed portion and to perform a forward and backward swinging move-

ment, said catch member being pivotally mounted on said arm and adapted to impart a limited rotational movement to said magazine, the backward movement of said arm being limited by the rear wall of said magazine case, whereby to limit the backward movement of said substitute bolt.

18. A sub-caliber assembly for use in a bolt-action rifle of the type including a bolt, a bolt case, a fixed barrel secured to the bolt case, and a magazine case open at the bottom, said assembly comprising; an insertion barrel constructed and arranged to be at least partly inserted into the bore of the fixed barrel and having a smaller caliber than said fixed barrel, a substitute bolt, a magazine frame constructed and arranged to be detachably fastened to the magazine case adjacent the bottom thereof, a pivot on said frame, a magazine carrier normally placed in said magazine case and mounted on said pivot, an axle secured to said magazine carrier, a cartridge magazine rotatably mounted on said axle and having a plurality of cartridge chambers for cartridges, a first spring adapted to swing said magazine carrier towards said insertion barrel, a plurality of projecting pins on said magazine, the number of said projecting pins being equal to the number of said cartridge chambers, a catch member, a second spring adapted to bring said catch member into engagement with said projecting pins, said substitute bolt having a recessed portion, and an arm pivotally mounted on said frame and adapted to engage said recessed portion and to perform a forward and backward swinging movement, said catch member being pivotally mounted on said arm and adapted to impart a limited rotational movement to said magazine, the backward movement of said arm being limited by the rear wall of said magazine case, whereby to limit the backward movement of said substitute bolt, said second spring being further adapted to move said arm into its backward end position.

19. A sub-caliber assembly for use in a bolt-action rifle of the type including a bolt, a bolt case, a fixed barrel secured to the bolt case, and a magazine case, said assembly comprising; an insertion barrel constructed and arranged to be at least partly inserted into the bore of the fixed barrel and having a smaller caliber than said fixed barrel, a substitute bolt, a rotatable cartridge magazine, means constructed and arranged to support said magazine in said magazine case, said magazine have a plurality of peripherally spaced cartridge chambers and a corresponding number of projecting pins, a catch member having a front finger and a rear finger adapted successively to cooperate with said projecting pins to impart limited rotational movement to said magazine whereby to bring said cartridge chambers successively into firing position relative to said insertion barrel, and means for transmitting movement from said substitute bolt to said catch member.

20. A sub-caliber assembly for use in a bolt-action rifle of the type including a bolt, a bolt case, a fixed barrel secured to the bolt case, and a magazine case, said assembly comprising; an insertion barrel constructed and arranged to be at least partly inserted into the bore of said fixed barrel and having a smaller caliber than said fixed barrel, a substitute bolt, a rotatable cartridge magazine, means constructed and arranged to support said magazine in said magazine case, said magazine having a plurality of peripherally spaced cartridge chambers and a corresponding

number of projecting pins, a catch member having a front finger and a rear finger adapted successively to cooperate with said projecting pins to impart limited rotational movement to said magazine whereby to bring said cartridge chambers successively into firing position relative to said insertion barrel, and means for transmitting movement from said substitute bolt to said catch member, said front finger being adapted during the backward movement of said substitute bolt to engage one of said projecting pins so as to rotate said magazine through an angle somewhat greater than the angular distance between two consecutive cartridge chambers.

21. A rifle as claimed in claim 20 and in which said front finger has a front abutment adapted upon angular movement of said magazine to come into contact with the next projecting pin in the series so as to prevent excessive rotational movement of said magazine due to the inertia thereof.

22. A sub-caliber assembly for use in a bolt-action rifle of the type including a bolt, a bolt case, a fixed barrel secured to the bolt case, and a magazine case, said assembly comprising; an insertion barrel constructed and arranged to be at least partly inserted into the bore of said fixed barrel and having a smaller caliber than said fixed barrel, a substitute bolt, a rotatable cartridge magazine, means constructed and arranged to support said magazine in said magazine case, said magazine having a plurality of peripherally spaced cartridge chambers and a corresponding number of projecting pins, a catch member having a front finger and a rear finger adapted successively to cooperate with said projecting pins to impart limited rotational movement to said magazine whereby to bring said cartridge chambers successively into firing position relative to said insertion barrel, and means for transmitting movement from said substitute bolt to said catch member, said rear finger having a front abutment adapted during the beginning of the forward movement of said substitute bolt to move a cartridge chamber towards the rear end of said insertion barrel, said substitute bolt being adapted to force said cartridge chamber finally into contact with said insertion barrel.

23. A sub-caliber assembly for use in a bolt-action rifle of the type including a bolt, a bolt case, a fixed barrel secured to the bolt case, and a magazine case, said assembly comprising; an insertion barrel constructed and arranged to be at least partly inserted into the bore of the fixed barrel and having a smaller caliber than said fixed barrel, a tubular member insertable into the bolt case, a substitute bolt slidable within said tubular member, a rotatable cartridge magazine, means constructed and arranged to support said magazine in said magazine case, said magazine having a plurality of cartridge chambers, a catch member adapted to engage said magazine for imparting limited rotational movement thereto, a recessed portion in said substitute bolt, and a pivotally mounted arm projecting into said recessed portion, said catch member being pivotally mounted on said arm, and said tubular member having an axial opening for said arm, catch member and magazine.

24. A sub-caliber assembly for use in a bolt-action rifle of the type including a bolt, a bolt case having an axial guide groove, a fixed barrel secured to the bolt case, and a magazine case, said assembly comprising; an insertion barrel constructed and arranged to be at least partly

inserted into the bore of said fixed barrel and having a smaller caliber than said fixed barrel, a tubular member insertable into the bolt case, a substitute bolt slidable within said tubular member, 5 a rotatable cartridge magazine, means constructed and arranged to support said magazine in said magazine case, said magazine having a plurality of cartridge chambers, a catch member adapted to engage said magazine for imparting limited rotational movement thereto, a recessed portion in said substitute bolt, a pivotally mounted arm projecting into said recessed portion, said catch member being pivotally mounted on said arm, and a guide bar secured to said tubular member and 10 adapted to engage said guide groove to prevent turning movement of said tubular member.

25. A sub-caliber assembly for use in a bolt-action rifle of the type including a bolt, a bolt case having an axial guide groove, a bolt stop member, a fixed barrel secured to the bolt case, and a magazine case, said assembly comprising; an insertion barrel constructed and arranged to be at least partly inserted into the bore of said fixed barrel and having a smaller caliber than said fixed barrel, a tubular member insertable into the bolt case, a substitute bolt slidable within said tubular member, a rotatable cartridge magazine, means constructed and arranged to support said magazine in said magazine case, said magazine 20 having a plurality of cartridge chambers, a catch member adapted to engage said magazine for imparting limited rotational movement thereto, a recessed portion in said substitute bolt, a pivotally mounted arm projecting into said recessed portion, said catch member being pivotally mounted on said arm, and a guide bar secured to said tubular member and adapted to engage said guide groove to prevent turning movement of said tubular member, said guide bar being 25 adapted to engage said guide groove to prevent turning movement of said tubular member.

30. A sub-caliber assembly for use in a bolt-action rifle of the type including a bolt, a bolt case having an axial guide groove, a fixed barrel secured to the bolt case, and a magazine case, said assembly comprising; an insertion barrel constructed and arranged to be at least partly inserted into the bore of said fixed barrel and having a smaller caliber than said fixed barrel, a tubular member insertable into the bolt case, guiding means on said tubular member cooperative with said guide groove, a substitute bolt slidable within said tubular member, a rotatable cartridge magazine, means constructed and arranged to support said magazine in said magazine case, said magazine having a plurality of cartridge chambers, means responsive to the movement of said substitute bolt for bringing said cartridge chambers successively into firing position relative to said insertion barrel, and means for connecting said insertion barrel with said tubular member.

35. A sub-caliber assembly for use in a bolt-action rifle of the type including a bolt, a bolt case having an axial guide groove, a fixed barrel secured to the bolt case, and a magazine case, said assembly comprising; an insertion barrel constructed and arranged to be at least partly inserted into the bore of said fixed barrel and having a smaller caliber than said fixed barrel, a tubular member insertable into the bolt case, guiding means on said tubular member cooperative with said guide groove, a substitute bolt slidable within said tubular member, a rotatable car-

tridge magazine, means constructed and arranged to support said magazine in said magazine case, said magazine having a plurality of cartridge chambers, means responsive to the movement of said substituted bolt for bringing said cartridge chambers successively into firing position relative to said insertion barrel, means for connecting said insertion barrel concentrically with said tubular member, and means for adjusting said insertion barrel in a certain angular position relative to said tubular member.

28. A sub-caliber assembly for use in a bolt-action rifle of the type including a bolt, a bolt case having an axial guide groove, a fixed barrel secured to the bolt case, and a magazine case, said assembly comprising; an insertion barrel constructed and arranged to be at least partly inserted into the bore of said fixed barrel and having a smaller caliber than said fixed barrel, a tubular member insertable into the bolt case, guiding means on said tubular member cooperative with said guide groove, a substitute bolt slideable within said tubular member, a rotatable cartridge magazine, means constructed and arranged to support said magazine in said magazine case, said magazine having a plurality of cartridge chambers, means responsive to the movement of said substitute bolt for bringing said cartridge chambers successively into firing position relative to said insertion barrel, and resilient means for connecting said insertion barrel with said tubular member, said resilient means comprising a helical spring inserted between said insertion barrel and said tubular member.

29. A sub-caliber assembly for use in a bolt-action rifle of the type including a bolt, a bolt case having an axial guide groove, a fixed barrel secured to the bolt case, and a magazine case, said assembly comprising an insertion barrel constructed and arranged to be at least partly inserted into the bore of said fixed barrel and having a smaller caliber than said fixed barrel, a tubular member insertable into the bolt case, guiding means on said tubular member cooperative with said guide groove, a substitute bolt slideable within said tubular member, a rotatable cartridge magazine, means constructed and arranged to support said magazine in said magazine case, said magazine having a plurality of cartridge chambers, means responsive to the movement of said substitute bolt for bringing said cartridge chambers successively into firing position relative to said insertion barrel, a locking member secured to said tubular member, and a groove in said substitute bolt, said locking member being adapted to engage said groove for locking said substitute bolt in firing position.

30. A sub-caliber assembly for use in a bolt-action rifle of the type including a bolt, a bolt case having an axial guide groove, a fixed barrel

secured to the bolt case, and a magazine case, said assembly comprising an insertion barrel constructed and arranged to be at least partly inserted into the bore of said fixed barrel and having a smaller caliber than said fixed barrel, a tubular member insertable into the bolt case, guiding means on said tubular member cooperative with said guide groove, a substitute bolt slideable within said tubular member, a rotatable cartridge magazine, means constructed and arranged to support said magazine in said magazine case, said magazine having a plurality of cartridge chambers, means responsive to the movement of said substitute bolt for bringing said cartridge chambers successively into firing position relative to said insertion barrel, a locking member secured to said tubular member and to said guiding means and extending radially into said tubular member, and a groove in said substitute bolt, said locking member being adapted to engage said groove for locking said substitute bolt in firing position.

31. A sub-caliber assembly for use in a bolt-action rifle of the type including a bolt, a bolt case, a fixed barrel secured to said bolt case and a magazine case, said assembly comprising; an insertion barrel constructed and arranged to be at least partly inserted into the bore of said fixed barrel and having a smaller caliber than said fixed barrel, a tubular member insertable in the bolt case, a substitute bolt slideable within said tubular member, a rotatable cartridge magazine, means constructed and arranged to support said magazine in said magazine case, said magazine having a plurality of cartridge chambers, a recessed portion in said substitute bolt, a pivotally mounted arm projecting into said recessed portion, a catch member for imparting a limited rotational movement to said magazine for bringing said cartridge chambers successively into firing position relative to said insertion barrel, said catch member being pivotally mounted on said arm, and a locking member secured to said tubular member and adapted to engage said recessed portion, whereby to lock said substitute bolt in firing position.

VICTOR HENRI WALLENBERG.
